S. D. Hopkins,

Spring,

No 9,215,

Patented Aug. 24, 1852.

UNITED STATES PATENT OFFICE.

S. D. HOPKINS, OF STAUNTON, VIRGINIA.

BED FOR INVALIDS.

Specification of Letters Patent No. 9,215, dated August 24, 1852.

To all whom it may concern:

Be it known that I, STEVENS D. HOPKINS, of Staunton, in the county of Augusta and State of Virginia, have invented certain new and useful Improvements in Sick-Couches, which I denominate the "Mechanical Nurse and Swing"; and I do hereby declare the following to be a full, clear, and exact description of the same, reference being had 5 to the accompanying drawing, making a part thereof, and which represents a perspective view of the entire apparatus.

The nature of my invention consists in arranging a frame upon or within which any ordinary bedstead may stand, with a sheet, hammock, or mattress, suspended from a carriage on top of said frame, so that it may be raised up, or rest upon the bed, as the case may be, or removed from over the bed, and 15 used as a swing for gently exercising, or for removing, the patient, from one bed to another, without lifting, as is usually done.

To enable others skilled in the art to make and use my invention, I will proceed to 20 describe the same with reference to the drawing.

A, represents the base of the frame, and B, the upright corner posts, and C the top cross braces for firmly supporting the sides 25 of the frame. The top longitudinal pieces D, of the frame may have a groove or track arranged thereon, in, or on which may move and be guided, the rollers or wheels E, on the carriage F. The carriage F, should 30 extend clear across the frame, and be braced and supported by the pieces G, and in or near the top of the carriage is arranged a shaft 35 or revolving axle H, having levers, arms, or their equivalents, inserted in one of its ends 40 for the purpose of turning it around. There should also be on the axle H a ratchet I, into which plays a pawl J, attached to the carriage, so as to hold the axle in any desired position. To the axle or roller H, is 45 suspended by the straps or cords K, a sheet, hammock or mattress R, upon which the patient lies, and which may be provided with a hole L, for placing the patient over the stool, without lifting or raising him or 50 her from the said hammock, or other equiv-

alent supporting thing. To the head piece or part of the sheet, hammock or other contrivance, is attached a cord M, which passes over a pulley N, attached to the carriage, and thence to the shaft of a crank O, arranged on the opposite end of the carriage from said pulley, and which crank or shaft, should be provided with a ratchet P, which may be held by a pawl, in a manner well known to mechanicians. This is for the 55 purpose of raising up the head, or upper part of the body of the patient, to give them such inclination as may be deemed essential to their comfort or convenience.

Q, is the bed over or around which the 60 frame may be placed, and may be of the kind in general use, or a fixture to the frame.

The patient may be gently exercised by raising up the mattress on which he lies, so as to be suspended clear of the bed, and 65 swinging it gently to and fro, and which has been found in practice to be essential to a 70 speedy restoration of health.

The object of my invention is, that the 75 patient shall always lie on the sheet, hammock, or other device, which may rest on the bed, or be suspended from the carriage by which it may be removed from one place to another, or in which the patient may be 80 gently exercised by swinging, and thus be moved from place to place, without lifting from the hammock on which he or she lies.

Having thus fully described the nature of 85 my invention, what I claim therein as new, and desire to secure by Letters Patent, is—

Suspending the sheet, hammock, or mattress, upon which the patient lies to a carriage which moves on a frame placed over or around a common bed, so that by said carriage the patient may be raised up, or 90 let down upon the bed, or moved from one place to another, or gently exercised, the whole being arranged, combined, and operating substantially in the manner herein described and fully shown.

S. D. HOPKINS.
